UNITED STATES PATENT OFFICE.

OTTO H. MOHR, OF KENTFIELD, CALIFORNIA.

DESIGN FOR A LIGHTING-FIXTURE.

44,216.

Specification for Design.

Patented June 17, 1913.

Application filed April 7, 1913. Serial No. 759,550. Term of patent 3½ years.

To all whom it may concern:

Be it known that I, OTTO H. MOHR, a citizen of the United States, residing at Kentfield, Marin county, State of California, have invented a new, original, and ornamental Design for Lighting-Fixtures, of which the following is a specification, reference being had to the accompanying drawings, forming part thereof.

Figure 1 is a vertical elevation of the

lighting fixture. Fig. 2 is a cross section of the fixtures.

I claim:

The ornamental design for a lighting fixture, substantially as shown.

OTTO H. MOHR.
